DESIGN FOR A COMBINATION COAL AND WOOD STOVE

Luther Thompson, Morganton, N. C.

Application June 29, 1940, Serial No. 93,332

Term of patent 14 years

To all whom it may concern:

Be it known that Luther Thompson, a citizen of the United States of America, residing at Morganton, in the county of Burke and State of North Carolina, has invented a new, original, and ornamental Design for a Combination Coal and Wood Stove, of which the following is a specification, reference being had to the accompanying drawing, forming a part thereof.

Figure 1 is an isometric view of a combination

coal and wood stove, embodying my design; and

Figure 2 is an isometric view of the stove looking from a direction opposite to that in Figure 1;

Figure 3 is a sectional view thereof on the line 3—3 of Figure 2.

I claim:

The ornamental design for a combination coal and wood stove, as shown.

LUTHER THOMPSON.
